UNITED STATES PATENT OFFICE.

RAYMOND A. HEISING, OF EAST ORANGE, NEW JERSEY, ASSIGNOR TO WESTERN ELECTRIC COMPANY, INCORPORATED, OF NEW YORK, N. Y., A CORPORATION OF NEW YORK.

MODULATED-WAVE TRANSMISSION.

Original application filed September 21, 1915, Serial No. 51,761. Patent No. 1,343,562, dated June 15, 1920. Divided and this application filed June 4, 1920. Serial No. 886,451.

To all whom it may concern:

Be it known that I, RAYMOND A. HEISING, a citizen of the United States, residing at East Orange, in the county of Essex, State 5 of New Jersey, have invented certain new and useful Improvements in Modulated-Wave Transmissions, of which the following is a full, clear, concise, and exact description.

This invention relates to systems for the 10 production and transmission of modulated oscillations. Modulated oscillations in a generic sense are oscillations of given characteristics, one or more of whose characteristics are varied in accordance with instantaneous conditions of a modulating device or means. More specifically, modulation refers to the variation in amplitude or intensity of a relatively high frequency electrical wave where the variation occurs in accordance with sound or electrical waves of a relatively low frequency.

Prior to this invention it has been known that if an electrical or thermionic discharge device of the type having an anode, a cathode and an impedance varying element is associated with suitable circuits, preferably including a tuned frequency-determining circuit and a source of energy, high frequency oscillations will be continuously generated. It has also been known that if a microphone or equivalent device is associated with such a circuit in a suitable manner to vary the potential of the impedance controlling element, the anode, or both 25 thereof, with respect to the cathode in accordance with speech waves or audible frequency waves acting upon the microphone or other element that the amplitude or intensity of the generated oscillations can be 30 made to vary to some extent in accordance with speech waves, so that the envelope of the higher frequency oscillations will be a more or less perfect representation of the modulating speech waves.

This invention has for an object to provide means whereby an improvement in the quality of the modulated waves produced by such an arrangement may be effected, thereby causing the variation of the high frequency waves to be such that a much more perfect reproduction of the modulating wave form can be had. The preferred form of

means for this purpose is an energy dissipating or resistance element of a suitable value serially included in the tuned circuit 55 of the thermionic device. Similar results, however, can be obtained by any equivalent means which will cause the envelope of the high frequency oscillations to perfectly reproduce the wave form of the modulating 60 waves.

The reason for the improved results obtained by the above described means is understood to be as follows: when a thermionic oscillation generator of the ordinary type is 65 set in operation, the intensity of the produced oscillations builds up rapidly until the high frequency energy dissipated in the system is equal to that produced from the direct current source of energy provided. 70 This condition is reached only when the oscillatory current generated contains harmonic frequencies in large proportions as compared with the fundamental or base frequency. The presence of these harmonics 75 results in a highly complicated rather than a simple harmonic wave form. When a modulating device acts upon a tube so oscillating, a small change in amplitude of the produced oscillations results also in a relatively large change in the proportion and 80 number of the harmonics present and thus produces considerable changes in the high frequency wave form. Such a process is therefore not one of changing a single high frequency wave in accordance with a modulating wave, but is one of changing in a different degree each of a number of waves of 85 harmonic frequencies. Instead, therefore, of producing a wave form which accurately 90 represents the speech to be transmitted a greatly distorted wave form results which is very inefficient for the transmission of speech.

By including a resistance of a proper value in the oscillation circuit the intensity of the normally produced oscillations is not only reduced but the harmonics are eliminated and the quality of speech transmitted is greatly improved. The envelope of the 100 high frequency waves is made to closely follow the wave form of the low frequency wave. While the amplitude of the generated oscillations and the quality of modulation

can be controlled by a resistance located in other parts of the circuit than the tuned circuit, the control will not then be as efficient. Other possible means for reducing the intensity of the oscillations produced also appear to be less desirable.

While the theory of operation of the preferred arrangement has been described in some detail the invention resides in the apparatus and not in the theory, and it is not intended to limit the invention to such theory but rather to state the probable explanation of the operation of the apparatus.

Referring to the drawing, Fig 1 represents one form of the invention in which a modulating and generating tube comprising the present improvement feeds into an amplifier for increasing the energy of the generated waves.

Figs. 2, 3, 4 and 5 illustrate other forms of circuit which may be substituted for the modulating and generating circuit of Fig. 1.

Referring particularly to Fig. 1 the elevated conductor 10 represents a suitable transmission circuit or conductor which is connected to earth at 11 through the inductance 12. The waves to be transmitted by the conductor 10 are produced by the generating tube 15 which has connected thereto a tuned circuit including the inductance 13 and a condenser 14. Conductors extending from one side of the condenser 14 and from an intermediate point in the inductance 13 lead to the input circuit of the tube 15, whose input electrodes comprise the usual heated filamentary cathode 16 and the grid or impedance controlling element 17. The anode 18 is connected to the terminal of the inductance 13 remote from the terminal connected to the grid 17. The usual battery 20 is placed in circuit with the anode and cathode.

The frequency of the oscillations in the output circuit is determined principally by the period of tuned circuit 13, 14, and the association of this tuned circuit with the tube or discharge device 15 cause the oscillations to be maintained. A resistance 30 and a battery 31 are included in the lead to the cathode 16, both these elements being shunted by the microphone 32. Sound waves acting upon the microphone 32 cause variations of potential of both the impedance controlling element 17 and the anode 18 with respect to the cathode 16. These speech frequency variations cause a corresponding variation in the high frequency power or energy fed into the oscillatory circuit 13, 14. In accordance with this invention there is inserted in the tuned circuit a preferably non-inductive and preferably adjustable resistance 35. In operating the system to transmit electrical waves, the resistance will be increased to a value suitable to produce good modulation as described above. In general this will be when the system is only

slightly oscillatory and is therefore producing a small amount of high frequency energy.

The energy of the oscillations produced may be directly transferred to a suitable transmitting conductor or antenna but in the present instance an amplifier 15 is provided by which the high frequency energy is increased. The coil 18 is for this purpose connected to the coil 23 included in the input circuit between the cathode 24 and the impedance controlling element 25 of the amplifier. A tuned circuit comprising a capacity 28 and the inductance 29 is connected between the cathode 24 and the anode 27, which constitute the output electrodes of the device 15. This circuit is preferably tuned to the same frequency as the circuit 13, 14. The electromagnetic coupling between coils 12 and 29 serves to transfer the amplified high frequency energy to the transmitting conductor. Referring to the circuit of the modulating tube, it will be seen that the microphone serves to affect the impedance controlling element 17 and the anode 18 in an additive manner, whereby an increase in the potential of each thereof tends to cause an increase in the intensity of the oscillations and vice versa.

In Fig. 2 a transformer 40 replaces the resistance 30 and the battery 31. The secondary of this transformer is included in the lead to the cathode, while the primary is in circuit with the battery 41 and the microphone 42. Sound waves acting upon the microphone 42 causes a variation in amplitude of the oscillations generated in a manner similar to that described in connection with Fig. 1. Reference characters common to Fig. 1 and the following figures represent corresponding elements.

In Fig. 3 an arrangement is shown in which the microphone acts to change the potential of the grid but not of the anode, in accordance with the speech waves. In this case the inductance 13 is divided in the middle and a large condenser 50, which has practically zero impedance for the high frequency currents, is inserted between the two parts thereof. Since such a condenser will not be of zero impedance for speech frequency currents, the transmitter 53 with its associated battery 52 and transformer 51 may be connected in parallel to the condenser 50 as shown. The potential variations of speech frequency are thus impressed upon the grid without being also impressed upon the anode or plate of the tube.

In the arrangement disclosed in Fig. 4, the speech frequency variations of potential are impressed upon the grid through a transformer 60 which is located between the condenser 14 and the grid 17.

Each of the systems described above depends for its modulating action upon the

variation of potential of one or more of the electrodes of the modulating discharge device or tube in accordance with speech. The arrangement of Fig. 5, however, does not

5 operate upon this principle. The modulation here is produced by the variable absorption of the high frequency waves by the microphone circuit. In order to accomplish this result, the resistance of the microphone 10 or transmitter is introduced into the oscillating circuit by coupling a tuned circuit thereto. The tuned circuit 70 includes the condenser 71, microphones 72 and the inductance 73. The whole circuit may be 15 adjusted to be resonant at the frequency to which the circuit 13, 14 is tuned. The inductances 70 and 13 are electromagnetically coupled. Changes in the resistance of the microphone will cause corresponding 20 changes in the amplitude of the oscillations produced in the tuned circuit 13-14, owing to the variable dissipation of energy in the circuit 70, as a result of these changes of resistance.

25 In each system described above the frequency of the high frequency oscillations may be determined by the setting of the condenser 14 and the value of the inductance 13. The amplitude of oscillations may be 30 adjusted from the greatest possible intensity almost to the critical point where oscillations cease, by adjusting resistance 35, without causing a substantial change in the fundamental frequency.

35 This application contains subject matter divided from my application Serial No. 51761, filed September 21, 1915, patented June 15, 1920, No. 1343562.

40 The novel features inherent in the invention are defined in the appended claims.

What is claimed is:

45 1. A modulating system comprising an electron discharge device, means including a tuned frequency-determining loop circuit associated therewith whereby said device generates high frequency oscillations of a definite frequency determined principally by the tuning of said circuit, means including a device for translating sound waves into 50 electrical variations for causing the oscillations generated thereby to vary in accordance with said sound waves, and a resistance in the tuned frequency-determining circuit of such a value as to restrain to a comparatively small intensity the oscillations produced.

55 2. A transmitting system comprising an electron discharge device having an anode, a cathode, and an impedance varying element, a tuned series-resonant circuit comprising inductance and capacity, separate leads from said inductance to said anode, cathode and impedance varying element respectively, said tuned circuit including 60 energy dissipating means whereby the oscil-

lations generated are of a relatively small intensity as compared with their intensity in the absence of such means.

3. A modulating system comprising an electron discharge device having an anode, 70 a cathode and an impedance varying element, a tuned series-resonant circuit comprising inductance and capacity, separate leads from said inductance to said anode, cathode and impedance varying element respectively, and a device associated therewith for varying in accordance with low frequency waves the oscillations produced by said device, said tuned circuit including a resistance of such value as to maintain 75 the working range of said discharge device upon a substantially straight portion of the space-voltage space-current characteristic thereof.

4. A transmitting system comprising an 80 electron discharge device having an anode, a cathode and an impedance varying element, a tuned series resonant circuit comprising inductance and capacity, and separate leads from said inductance to said anode, 85 cathode and impedance varying element respectively, a device for varying at a relatively low frequency rate the oscillations produced by said discharge device, and a resistance included in said tuned circuit.

5. A telephone transmission system comprising an evacuate electron discharge tube having an anode, a cathode and an impedance varying element, an output circuit, an input circuit, a feed-back connection between said circuits, and a tuned circuit associated with said device and with each of said circuits, a source of space current for energizing said device whereby oscillatory currents are caused to be produced in 100 said tuned circuit, a resistance of such value as to limit the produced oscillations to an amplitude small as compared with the maximum possible amplitude included in said tuned circuit, and a device for varying in 105 accordance with sound waves the potential of said impedance varying element with respect to said cathode.

6. A telephone transmission system comprising an evacuated electron discharge tube 115 having an anode, a cathode and an impedance varying element, an output circuit, an input circuit, a feed-back connection between said circuits and a tuned circuit associated with said device, a source of space current, a resistance in said tuned circuit, and a device for varying in accordance with sound waves the potential of said anode with respect to said cathode.

7. A telephone transmission system comprising an evacuated electron discharge tube 125 having an anode, a cathode and an impedance varying element, an output circuit, an input circuit, a feed-back connection between said circuits and a tuned circuit as-

sociated with said tube, a source of space current, a resistance in said tuned circuit, and a device for synchronously varying in accordance with sound waves the potentials 5 of said impedance varying element and said anode with respect to said cathode.

8. A system, for producing oscillations of carrier frequency the envelope of which accurately represents the variations of a speech 10 wave which system comprises a space discharge device having a cathode, an anode, and a control element, suitable circuits including impedance elements, and a source of electromotive force of a given value for generating oscillations; and a device for introducing impedance variations of speech frequency into the said system whereby the carrier frequency waves are varied in amplitude, said impedance elements being so 15 designed, proportioned, and related to each other and to said device that the total oscillatory energy is measurably less than is produced by the same discharge device with 20

the same given value of electromotive force when its circuits are adjusted for maximum 25 total oscillatory energy output.

9. The method of producing oscillations of carrier frequency, the envelope of which varies to accurately follow the variations of a low frequency modulating wave by means 30 of an electron discharge device comprising an anode, a cathode and a grid, suitable circuit connections, and a source of energizing electromotive force whereby the carrier frequency oscillations are generated; which 35 comprises establishing oscillations of small energy in said device as compared with the energy when said device, supplied with an equal electromotive force, is producing the largest possible oscillations, and introducing the low frequency modulating wave variations into the circuit connections of said device 40

In witness whereof, I hereunto subscribe my name this 27th day of May, A. D. 1920.

RAYMOND A. HEISING.
